(57) **CLAIM**

The ornamental design for a play mat set, as shown and described.

DESCRIPTION

FIG. 1 is a top, front and left side perspective view of the play mat set of our design in accordance with a first embodiment.

FIG. 2 is a left side view thereof.

FIG. 3 is a right side view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a top, front and left side perspective view of the playmat of our design in accordance with a second embodiment.

FIG. 9 is a left side view thereof.

FIG. 10 is a right side view thereof.

FIG. 11 is a front elevation view thereof.

FIG. 12 is a rear elevation view thereof.

FIG. 13 is a top plan view thereof.

FIG. 14 is a bottom plan view thereof.

FIGS. 15-30 are top plan views of sixteen different configurations of the components of the second embodiment in respective environments as follows:

FIG. 15 is a top plan view of a first configuration;

FIG. 16 is a top plan view of a second configuration;

FIG. 17 is a top plan view of a third configuration;

FIG. 18 is a top plan view of a fourth configuration;

FIG. 19 is a top plan view of a fifth configuration;

FIG. 20 is a top plan view of a sixth configuration;

FIG. 21 is a top plan view of a seventh configuration;

FIG. 22 is a top plan view of a eighth configuration;

FIG. 23 is a top plan view of a ninth configuration;

FIG. 24 is a top plan view of a tenth configuration;

FIG. 25 is a top plan view of a eleventh configuration;

FIG. 26 is a top plan view of a twelfth configuration;

(Continued)

FIG. 27 is a top plan view of a thirteenth configuration; FIG. 28 is a top plan view of a fourteenth configuration; FIG. 29 is a top plan view of a fifteenth configuration; and, FIG. 30 is a top plan view of a sixteenth configuration. Elements drawn in broken lines in FIGS. 15-30 correspond to environmental elements which form no part of the claimed play mat set design.
